UNITED STATES PATENT OFFICE.

HENRY A. WEIHMANN, OF PHILADELPHIA, PENNSYLVANIA, ASSIGNOR TO
SIMONS BRO. & CO., OF SAME PLACE.

DESIGN FOR A HANDLE FOR KNIVES.

SPECIFICATION forming part of Design No. 21,785, dated August 23, 1892.

Application filed February 1, 1892. Serial No. 420,017. Term of patent 14 years.

To all whom it may concern:

Be it known that I, HENRY A. WEIHMANN, a citizen of the United States, residing at Philadelphia, in the county of Philadelphia and 5 State of Pennsylvania, have invented and produced a new and useful Design for Handles of Knives, of which the following is a specification, reference being had to the accompanying drawing, illustrating the design.

10 The drawing is a plan view of a handle of a knife, showing my design.

The leading feature of the design is the particular ornamental scroll-pattern shown arranged about the edge of the face of the handle, with the surface included within the or-

namentation plain or unornamented. The ornamental pattern does not itself constitute the extreme edge of the handle, so as to form an irregular ornamental edge thereon, but is placed adjacent to the extreme smooth edge 20 of the handle, leaving a slight unornamented border, as shown.

What I claim as new, and desire to secure by Letters Patent, is—

25 The design for handles of knives, substantially as shown and described.

HENRY A. WEIHMANN.

In presence of—

ERNEST HOWARD HUNTER,
C. M. DIETTERICH.
